ABSTRACT: A foot powder applicator comprising a plastic package formed in the shape of an oversized sock. The package includes a quantity of foot powder therein and is openable on its top end for insertion of the user's foot. Thus, the applicator may be utilized to package foot powder and may be opened for application of the powder. The user's foot is inserted in the open package and the upper portion thereof clasped to hold it around the ankle, and the foot shaken to apply powder uniformly thereto.

1
FOOT POWDER APPLICATOR**BACKGROUND OF THE INVENTION**

1. Field of the invention

The present invention relates generally to foot-powder applicators and more particularly to a foot-powder applicator which also serves as a package.

2. Description of Prior Art

It has been common practice to provide foot-powder containers which include perforated dispensing heads and/or spray means. Also, protective socks have been proposed for being worn by a patient after application of ointment or medication. However, there are no prior art foot-powder applicators known to applicant which include a flexible container in which the foot-powder is packaged for sale and which may be opened on its top end and the user's foot inserted therein to utilize such container for applying foot-powder directly to the foot.

SUMMARY OF THE INVENTION

The present invention is characterized by a flexible package having a foot-receiving portion and an ankle-receiving portion. The package is sold with a quantity of foot-powder contained therein and when it is to be used, the upper end of the package is opened and the foot inserted, the upper portion thereof clasped around the user's ankle, and the foot shaken to thoroughly apply the powder.

Other objects and features of the present invention will become apparent from the following description when taken in conjunction with the accompanying drawing:

DESCRIPTION OF THE DRAWING

FIG. 1 is a perspective view of a foot-powder applicator embodying the present invention;

FIG. 2 is a vertical sectional view taken along the line 2-2 of FIG. 1;

FIG. 3 is a perspective view, in reduced scale, of the applicator shown in FIG. 1 during application of powder; and

FIG. 4 is a perspective view, in reduced scale, of the applicator shown in FIG. 1 being removed from a protective box.

DESCRIPTION OF THE PREFERRED EMBODIMENT

The foot-powder applicator shown in the preferred embodiment includes a plastic package 11 formed in the shape of an oversized sock and including a foot-receiving portion 13 and an ankle-receiving portion 15. The package 11 may be made from one piece of thin plastic which is folded back on itself and adhered at its marginal edges to form a heat-seal 17 extending downwardly at the front edge of the leg-receiving portion 15 and along the top of the instep of the foot-receiving portion 13. Also, the plastic forming the package is adhered together at its lower marginal edges to form a heat-seal 19 extending longitudinally beneath the foot-receiving portion 13.

A quantity of foot-powder 23 is included in the bottom of the foot-receiving section 13 and the upper extremities of the side of the leg-receiving portion 15 is collapsed together and sealed at 25. The lower extremity of the seal 25 is formed with a transverse crease 27 which forms a weakened line for convenient opening of the package 11.

Preferably the package 11 will be folded into a compact unit and housed in a box 31 (FIG. 4) for display on drugstore shelves and the like.

As described above, the package 11 is folded into a compact unit and received within the box 31 and will be removed therefrom for application of the foot-powder 23. After removal from the package 31, the package 11 will be unfolded and the upper extremity 25 removed by tearing along the

crease 27. The user will then grasp the upper extremity of the package 11 and hold the leg-receiving portion 15 open for insertion of the foot 33 into the foot-receiving portion 13. The leg-receiving portion 15 is then clasped and squeezed against the user's leg 35 to prevent escape of the powder 23 while the foot 33 is shaken. By merely shaking the foot 33 three or four times, the powder 23 will be applied uniformly to all surfaces of the foot 33, including the bottom, sides, top, back, and between the toes. Experience has proven that such a procedure will normally provide application of the proper amount of foot-powder 23 but if the foot is a little moist an excessive amount of powder may adhere thereto. Such excessive powder may be removed by merely brushing the package 11 inwardly against the surface of the foot 33 to cause the excess powder to fall downwardly into the bottom of the package 11, thus avoiding direct hand contact with the powder. Consequently, convenient, rapid and effective application of the powder 23 is accomplished without messy sprinkling, spraying, or waste of powder.

From the foregoing description it will be apparent that the foot-powder applicator of present invention provides a convenient means for packaging foot-powder for sale and also for application of such powder. The combination package and applicator is relatively inexpensive to manufacture and will provide for proper application of powder in a rapid and efficient manner thereby encouraging use of foot-powder and preventing waste of the powder. The package may conveniently be made sufficiently large to enable all persons, from the smallest child to the biggest athlete, to utilize a common size without the necessity of providing numerous differently sized packages. Further, after use the package can be conveniently folded over on its top end to form a seal and then folded to form a compact package for packing in a suitcase or storing in a dressing locker.

Various modifications and changes may be made with regard to the foregoing detailed description without departing from the spirit of the invention or the scope of the following claims.

I claim:

1. A combination package and foot-powder applicator for treating a patient's foot, said applicator comprising:
an elongated nonporous package formed in its bottom portion with a foot-receiving portion for loosely receiving said foot and in its upper portion with a leg-receiving portion for overfitting said patient's ankle, said leg-receiving portion terminating in its top end with an inlet;
a quantity of loose foot-powder disposed in said package;
and
sealing means for sealing said inlet to retain said powder in said package whereby said foot-powder may be packaged in said package and when said foot is to be treated said package may be opened on its top end and said foot inserted into said foot-receiving portion and said leg-receiving portion closed around said ankle and said foot shaken to disperse said foot-powder throughout said relatively loose fitting foot portion for thorough application to said foot while said leg portion is tightly clasped around said ankle to hold said loose foot-powder captive in said package.

2. A foot-powder applicator as set forth in claim 1 wherein said package is made of plastic.

3. A foot-powder applicator as set forth in claim 1 wherein said package includes a weakened crease across its upper extremity.

4. A foot-powder applicator as set forth in claim 1 that includes a box for receiving said package.

5. A foot-powder applicator as set forth in claim 1 wherein said package is formed in the shape of an oversized stocking.
